UNITED STATES PATENT OFFICE.

REBECCA E. HOOPER, OF HALF MOON BAY, CALIFORNIA.

HOLDER AND RULING DEVICE FOR TABLETS.

Application filed March 3, 1926. Serial No. 91,869.

This invention relates to a pad or tablet holder and a ruling device to cooperate therewith.

The object of the present invention is to generally improve and simplify the construction and operation of devices of the character described, to provide a holder to which a pad or tablet of paper may be readily applied and secured, to provide a ruling attachment and scales whereby the paper may be marked, lined or ruled as desired, and, further to provide a detachable cover member whereby written matter on the pad may be concealed by the cover or disclosed by transverse movement for the purpose of permitting study in memory work as in school work, at home, or otherwise.

One form which my invention may assume is exemplified in the accompanying drawing, in which—

Fig. 1 is a plan view of a holder showing the paper pad and ruling device in position thereon.

Fig. 2 is a side elevation of the same.

Fig. 3 is a perspective view of the slotted tube whereby one of the rulers is supported.

Fig. 4 is a cross-section on line IV—IV, Fig. 1.

Referring to the drawings in detail and particularly Figs. 1 and 2, A indicates a base member or holder constructed of wood or any other suitable material. This base or holder is preferably rectangular in shape as shown, and it serves the purpose of supporting and securing a pad or paper such as indicated at 3. Extending under the upper end of the holder is a strip of steel or like material which is suitably secured to the holder. This steel is longer than the width of the base so as to provide two projecting ends as indicated at 2—2. Carried by the projecting ends are upwardly extending threaded bolts 3—3 and heads or bolts 4.

Adapted to be placed on top of the holder is a tablet or number of sheets of paper such as indicated at 5, and adapted to secure the pad of paper to the holder is a cross-bar 6, the ends of which are perforated to pass over the bolts 3 so that the bar may be clamped on top of the paper by means of the nuts 4. The cross-bar 6 is graduated on one edge as at 7 to form a scale, the function of which will hereinafter be described. Extending upwardly adjacent the ends of the cross-bar or scale just referred to are a pair of posts 8—8 on the upper ends of

which is permanently secured a rod 9. Slidably and turnably mounted on the rod is a tube 10, see Figs. 1, 2 and 3, and secured to the central portion of the tube is 60 a sleeve member 11, on the forward side of which is formed a pair of projecting hinge lugs 12—12.

Disposed at right angles to the scale or rule 6 is a second rule 13 which is graduated 65 as at 14. Attached to the upper end of this rule is a bracket plate 15 and formed thereon is a pair of hinge lugs 16 which are adapted to extend between the hinge lugs 12 on the sleeve 11. A pin or rod passes 70 through the respective hinging lugs as shown at 17 and pivotal movement of the rule 13 is thus permitted with relation to the rule 6 so that the rule 13 will always lie flat on top of the pad or tablet 5, regardless 75 of the number of sheets of paper placed on the holder A.

By referring to Fig. 3, it will be noted that the tube 11 is slotted at opposite ends as indicated at 19 and 20. These slots extend 80 to the sleeve 11 and they permit sliding movement of the tube from the central position shown in Fig. 1 to either side of the central position to a point where one end or the other of the bushing 11 will engage 85 the posts 8. At this point either edge of the rule 13 will line up with the outer edges of the paper and further movement is accordingly not required. The stopping of the slots at this point is of further importance 90 as it prevents disengagement or loss of the parts accidentally or otherwise.

Slots 19 straddle the posts 8 when the tube and the rule 13 are moved laterally across the pad and it is mainly for this reason that 95 they are provided, otherwise the tube pivots on the rod, and, in fact, it also pivots when moved laterally, as the width of the slot 19 and 20 is sufficient to permit pivotal movement which is necessary in conjunction 100 with the hinge lugs 12 and 16 to permit the rule 13 to lie flat on the pad. Lateral movement of the tube 10 and rule 13 permits the pad to be ruled vertically. The vertically 105 ruled lines may be measured or spaced apart by using the scale 7. The ruled lines may be drawn along either edge of the rule 13 or by inserting the pencil in the ferrule 22 which is slidable from end to end in the slot 23 formed in the rule 13. This ferrule may also be used for lining or ruling the paper 110 horizontally, the distance between the ruled

lines, if desired, being measured on the scale 14.

The device as a whole may be used for office work, school work or the like, but preferably for school work as it may be used in a number of studies. It will also be noted that the rule 13 is provided with a pair of spring clips such as shown at 24. A cover member indicated by dotted lines at 25 may 10 be inserted under the clips and retained thereby, and this cover may be used in connection with memory studies, for instance, the pad may contain written matter which it is desired to memorize. In that case the rule 15 carrying the cover member 25 is moved laterally to cover up the work and the student repeats the written matter by memory, but, if unable to do so, may disclose the work by moving the rule and cover laterally to 20 uncover the same.

The device may also be used to advantage in the study of geometry and trigonometry as it materially aids in drawing numerous figures and symbols required. For memory 25 study it is obvious that the device may be used both for elementary and advanced work. For instance, words may be written in column formation and concealed or uncovered as desired by lateral movement of 30 the rule and cover member, this being of particular advantage in teaching shorthand, spelling, foreign languages and even in learning the multiplication table as in elementary school work.

If it is desired to renew the pad or sheets 35 of paper mounted on the holder A, it is only necessary to release the nuts 4 and to lift the cross-bar or rule 6 vertically out of engagement with the posts. The stubs of paper 40 remaining are removed and a new pad is inserted. The rule is then replaced and the nuts applied and tightened to securely hold the pad.

The entire device is exceedingly simple in 45 substantial construction and while certain

features thereof are more or less specifically described and illustrated changes may be made within the scope of the appended claims to suit varying conditions and the judgment and experience of the manufacturer.

Having thus described my invention what I claim and desire to secure by Letters Patent is—

1. A device of the character described 55 comprising a holder, a detachable clamping bar mounted transversely thereon and adapted to clamp a pad of paper on the holder, a rod supported by the bar and elevated with relation thereto, a sleeve slidable longitudinally on the bar and also turnable thereon, and a ruler hingedly secured to the sleeve and disposed at right angles to the clamping bar.

2. A device of the character described 65 comprising a rectangular shaped plate-like holder, a pair of threaded bolts at one end thereof, said bolts being disposed at the corners of the holder, a clamping bar disposed transversely of the holder, and having perforated ends to pass over the threaded bolts, clamping nuts carried by said bolts and adapted to force the clamping bar downwardly against the holder to clamp and secure a pad of paper, a pair of posts on the 70 clamping bar one at each end thereof, a rod supported by said posts and slightly elevated with relation to the clamping bar, a sleeve mounted on the rod and of substantially the same length as the rod, a second sleeve 75 surrounding the first named sleeve and secured thereto, a pair of hinge lugs on said second named sleeve, a ruler hingedly secured between said lugs and disposed at right angles to the clamping bar, said first named sleeve being slotted at opposite ends to permit longitudinal movement of the sleeve on the rod and said sleeve being also turnable on the rod.

REBECCA E. HOOPER.
